UNITED STATES PATENT OFFICE.

WILLIAM H. MOZINGO, OF HURDLAND, MISSOURI, ASSIGNOR OF ONE-HALF TO ARLE E. EASLY, OF LA PLATA, MISSOURI.

DOOR-LOCK.

1,245,367.

Specification of Letters Patent.

Patented Nov. 6, 1917.

Application filed April 5, 1917. Serial No. 159,989.

To all whom it may concern:

Be it known that I, WILLIAM H. MOZINGO, a citizen of the United States, residing at Hurdland, in the county of Knox and 5 State of Missouri, have invented a new and useful Door-Lock, of which the following is a specification.

The present invention appertains to locks and latches, and aims to provide a novel and 10 improved device of that character for use upon doors and the like and comprising a novel assemblage of the component elements to enhance the utility and efficiency of the lock.

15 Another object of the invention is the provision of a lock which can be readily applied to a door or other object, and which can be reversed easily.

Another object of the invention is the 20 provision of a lock having a double lock bolt and novel means for mounting and actuating the same.

A still further object of the invention is 25 the provision of novel means for locking and releasing the double lock bolt.

It is also the object of the invention to provide a lock of the nature indicated which is comparatively simple, compact and inexpensive in construction, and which is durable and efficacious.

With the foregoing and other objects in view which will appear as the description proceeds, the invention resides in the combination and arrangement of parts and in 35 the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a median section of the lock 45 taken on the line 1—1 of Fig. 2, portions being shown in elevation.

Fig. 2 is an edge view of the door and lock.

Fig. 3 is a section on the line 3—3 of 50 Fig. 1.

Fig. 4 is a perspective view of the rocker or cam.

Fig. 5 is a fragmental view illustrating 55 the key receiving means.

Fig. 6 is a perspective view of the partition disks.

Fig. 7 is an elevation of the key used for turning the detent.

In carrying out the invention, there is provided a pair of adjacent parallel tubular 60 casings 1 coextensive in length and disposed side by side, and said casings can be readily applied by drilling two bores 2 in the door or other object 3 to mortise the lock within the door, and the casings can be readily reversed for reversing the lock. A face plate 4 is attached to the outer or forward ends of the casings 1 which have the lugs or lips 5 extending through slots 6 in the face plate 4 and swaged to secure the parts together. 70 Two of the lugs 5 of the two casings extend through the same slot to hold the casings together. The apertured end portions of the plate 4 can be secured to the edge of the door by means of screws 7 or other means 75 engaged through the plate 4 and taking into the door. A cylindrical lock or latch bolt 8 is slidable within each casing 1, and said bolts are provided at their outer or forward ends with reduced beveled portions 9 extending through openings 9' of the plate 4 to snap into engagement with the keeper (not shown) for holding the door in closed position. The bolts 8 in seating against the plate 4 are limited in their outward movement.

In order to project the bolts, springs are provided. For this purpose, partition disks 10 are fitted within the casings 1 in rear of the bolts 8 and are connected by a web 90 11 extending through longitudinal slots 12 with which the adjacent portions of the casings are provided, said slots 12 extending to the rear or inner ends of the casings, in order that the disks 10 can be inserted from 95 the rear. The disks 10 are held in place by means of rivets or pins 13 extending through the casings 1 behind the disks, and coiled wire expansion springs 14 are disposed within the casings and are confined between 100 the disks 10 and rear ends of the bolts 8 for projecting said bolts or the portions 9 thereof.

As a means for uniting the bolts 8 for simultaneous operation, a U-shaped yoke 15 105 is provided, the limbs thereof projecting forwardly and sliding along the opposite sides of the casings 1 within the same. The

5 terminals of the yoke 15 are received by recesses 16 with which the bolts 8 are provided, and said terminals are bent at an angle, as at 17, to be embedded within the

5 bolts 8 whereby the bolts and yoke move together, the yoke connecting the bolts so that they move as a unit. The limbs of the yoke 15 slide through notches 19 provided in the opposite edges of the disk 10, and

10 the intermediate portion of the yoke projects through and is movable longitudinally within the slot 12, said intermediate portion being indented, as at 18.

15 The means for retracting the bolts or double bolt, embodies an elliptical rocker or cam 20 extending through the slot 12 with its ends projecting into the two casings, and said rocker 20 has a non-circular opening 21 between its ends through which the knob 21 between its ends through which the knob 21

20 spindle 22 extends from one side of the door to the other between the casings 1 at right angles to the common plane thereof, suitable knobs 23 being secured upon the ends of said spindle for rocking the rocker 20 in either direction. The rocker is provided

25 with a peripheral groove 25 to fit the yoke 15, which is preferably bent from a rod, and when the rocker is oscillated in either direction, one end portion thereof will engage the

30 intermediate portion of the yoke 15 and move toward the indent 18 for forcing the yoke inwardly to retract the bolts 8, and when the knob is released, the springs 14 will again project the bolts and return the

35 rocker 20 to normal transverse position.

Side plates 24 are secured to the opposite sides of the door 3, and can serve as bearings for the spindle 22.

40 In order to lock the bolts 8 in projected position, they are provided at adjacent portions with confronting rounded notches 25, and a transverse cylindrical detent 26 is rotatable in the adjacent portions of the casings 1 and in a transverse bore 26' with

45 which the door is provided. The detent 26 has diametrically opposite rounded notches 27 for the passage of the bolts 8, while the notches 25 of the bolts are adapted to receive the web of the detent between the

50 notches 27 when the detent is turned.

55 In order to conveniently turn the detent from the inside, a tongue 28 has a portion 29 journaled through the inner plate 24, and the free end of the tongue is seated within a slot 30 with which the inner end of the

55 detent is provided, whereby the detent turns with the tongue. A finger piece 31 is attached to the portion 29, and can be readily swung to turn the detent.

60 The detent 26 is held between the tongue 28 and a pin 32 projecting inwardly from the outer plate 24, the pin 32 having a reduced portion 33 engaged through said plate, and the free end of the pin 32 pivotally engaged the outer end of the detent 26. This will

prevent the detent from shifting longitudinally of itself out of place, but enables the detent to be rotated easily. The outer end of the detent has a slot 34 for the engagement of a suitable key, such as illustrated in Fig. 7.

70 A disk 35 is pivoted upon the outer portion 33 of the pin 32 and has diametrically opposite radial slots 36, while the outer plate 24 has arcuate slots 37.

75 The key embodies a pair of levers 39 pivoted between their ends, as at 40, to a connecting piece 41, and said levers 39 have overlapping finger pieces 42 at one end, and key bits 43 at the other end. By inserting the bits 43 through the slot 36, and swinging the finger pieces 42 away from one another, the bits 43 are swung toward one another to properly engage in the slot 35 of the detent, whereby the key can be turned for turning the detent, the slots 37 limiting the turning movement of the key to either bring the detent to locking or releasing position. When the detent is turned to the position illustrated in Figs. 1 and 3, the bolts 8 can be 80 retracted, since they can slide through the notches 27 of the detent, but when the bolts are projected and the detent turned through substantially one quarter of a circle, the detent will be brought within the notches 25, 95 thereby preventing the retraction of the bolts, and thus locking them.

90 Having thus described the invention, what is claimed as new is:—

100 1. A device of the character described embodying a pair of casings, a bolt slideable in each casing, a yoke connecting the bolts, said casings having slots in which the yoke works, and means engaging the yoke for reTRACTING THE BOLTS.

105 2. A device of the character described embodying a pair of casings, a bolt slideable in each casing, a yoke connecting the bolts, said casings having slots in which the yoke works, and a rocker extending through said 110 slots into the casings and engageable with the intermediate portion of the yoke for reTRACTING THE BOLTS.

115 3. A device of the character described embodying a pair of casings, a bolt slideable in each casing and projectable from one end thereof, the casings having adjacent slots extending to the other end thereof, partitions fitted within the casings and having a connecting web within said slots, spring 120 means between the bolts and partitions, and means for retracting the bolts simultaneously.

125 4. A device of the character described embodying a pair of slideable bolts, means for retracting them, and a detent movable between the bolts to releasing and locking positions and preventing the movement of the bolts when in locking position.

130 5. A device of the character described em-

bodying a pair of bolts having adjacent notches, means for retracting the bolts, and a rotatable detent movable into said notches, and having notches for the passage of the 15
5 bolts.

6. A device of the character described embodying a pair of casings, a bolt slidable within each casing, and a detent movable between the casings for locking both bolts.

10 7. A device of the character described embodying a pair of casings, a bolt slidable in each casing, and having a notch, and a detent

rotatable in the adjacent portions of the casings and movable into said notches, the detent having notches for the passage of the 15
bolts.

In testimony that I claim the foregoing as my own, I have hereto affixed my signature in the presence of two witnesses.

WILLIAM H. MOZINGO.
